UNITED STATES PATENT OFFICE.

FRANK P. KOBERT, OF AMITYVILLE, NEW YORK.

ART OF METAL-WORKING.

1,333,081.

Specification of Letters Patent.

Patented Mar. 9, 1920.

Application filed October 21, 1916, Serial No. 126,817. Renewed August 8, 1919. Serial No. 316,206.

To all whom it may concern:

Be it known that I, FRANK P. KOBERT, a citizen of the United States, and residing at Amityville, L. I., in the county of Suffolk 5 and State of New York, have invented certain new and useful Improvements in the Art of Metal-Working, of which the following is a specification, such as will enable those skilled in the art to which it appertains 10 to make and use the same.

This invention relates to metal working machines and particularly to what are known as forging, heading, upsetting, riveting and welding machines, and the invention 15 involves an improvement in machines of this class particularly designed for making certain articles of manufacture, and an improved method of operating such machines to form such articles; one object of 20 the invention being to provide an apparatus of the class specified whereby a predetermined article such for illustration as a puppet valve may be quickly and easily formed by a plurality of successive operations without 25 changing or altering in any way the machine or apparatus, or the parts thereof; the invention also comprising an attachment which may be applied to well known forms of electric riveting machines or apparatus, 30 such for instance as that shown and described in U. S. Letters Patent No. 1,139,300, granted to me May 11, 1915, and which covers an electric riveting apparatus involving many of the features of construction shown 35 and described herein.

The invention described and claimed herein is also an improvement on that described and claimed in a prior application for Letters Patent of the United States filed by 40 me May 9, 1916, Serial No. 96,314, and covering an electric riveting machine, and whereby said electric riveting machine is converted into a forging machine for the production of articles of manufacture.

45 The invention is fully disclosed in the following specification, of which the accompanying drawing forms a part, in which the separate parts are designated by suitable reference characters in each of the 50 views, and in which:—

Figure 1 is a side view of a power press or apparatus provided with my improvement;

Fig. 2 a front view thereof with part of 55 the construction broken away;

Fig. 3 a partial section on the line 3—3 of Fig. 2 and on an enlarged scale;

Fig. 4 a partial section on the line 4—4 of Fig. 3;

Fig. 5 a partial section on the line 5—5 60 of Fig. 1; and

Fig. 6 a view showing the successive steps or operations in producing a puppet valve with my improvement.

In the drawing forming part of this specification, I have shown at *a* the frame of a power press which may be of the usual or any preferred form and construction, but which is preferably of the form and construction shown in the application herein-before referred to.

Mounted in front of the bottom portion of the main frame is a work supporting table *b* having a bottom openwork portion *b*², and said table is vertically movable. The 75 table *b* may be connected with the side portions of the main frame in the usual or any desired manner, preferably by a tongue and groove construction, and set screws *b*³ are employed to hold said table at any desired point of adjustment.

The table *b* is made vertically adjustable by means of a vertically arranged shaft *c* which has a bearing in the bottom body portion of said table, and in the base *a*² of the main frame, and the upper end portion of said shaft is provided with a beveled gear *c*², and mounted at right angles to said shaft is a supplemental shaft *c*³ provided with a pinion *c*⁴ which meshes with the gear *c*², 90 and at its outer end with a hand wheel *c*⁵. The lower end portion of the shaft *c* is screw-threaded and passes into a correspondingly threaded bushing *c*⁶ mounted in the base *a*² of the main frame, and by means 95 of this construction the table *b* may be raised or lowered and adjusted to any desired position.

Mounted in the central back portion of the main frame above the table *b* is a main 100 power and crank shaft *d*, and mounted in the front top portion of the main frame is a vertically movable plunger carriage *e* which is held in position by vertical strips *e*² secured to the top portion of the main 105 frame, and in the bottom portion of the plunger carriage is a curved space or chamber *e*³ which opens downwardly through a corresponding curved slot *e*⁴. This construction is also similar to that shown and 110 described in the application above referred to, with the exception of the bottom of the plunger carriage *e* which is widened to permit of the lengthening of the chamber *e*³.

in the bottom of the plunger carriage and the slot e^4 .

In this improvement, I provide a plunger f which is box-shaped or recessed in form 5 and which comprises a back, top, bottom and sides, and which will be hereinafter described in detail.

Mounted in the main frame rearwardly of the plunger f is an electrode carrier and 10 plunger guide g horizontally rotatable on a vertical shaft g^2 and the part g is provided with a forwardly extending and vertically arranged head g^3 in which the plunger f is mounted and vertically movable, and 15 mounted in one side portion of the head g^3 is a vertically movable electrode support h , which is cylindrical in form and provided at its lower end with an enlarged head h^2 with which is connected an electrode i , the 20 construction of which is or may be the same as in the application hereinbefore referred to.

The head g^3 of the part g is provided with a slot h^3 through which is passed an arm i^2 25 which also passes through the electrode support h as in the patent and application hereinbefore referred to, and the arm i^2 is pivoted to the central portion of the part g at i^3 , and said arm is provided at its outer 30 end with a handle i^4 and the inner end portion of said arm is provided with a weight i^5 which normally holds the outer end of said arm and the electrode support h in their highest position.

35 The top of the electrode carrier and plunger guide g is provided with a backwardly directed extension g^5 to the bottom of which is secured a transverse block or plate j , and beneath the rear end portion of 40 the part g^5 is a transverse shaft k provided at one end with a backwardly directed arm k^2 with which is connected a rod k^3 , which is connected at k^4 with a treadle k^5 , in the bottom of the frame, and mounted on the shaft 45 k is a clamp block k^6 of the usual form, and which operates in connection with the block or plate j , and mounted in one side of the main frame is a stop screw k^7 which operates in connection with the part g^5 of the electrode carrier and plunger guide g to limit 50 the horizontal rotary movement of said part g in one direction.

Mounted in the top portion of the main frame on the transverse shaft m is a rock beam m^2 which is secured to said shaft, and provided at its front end with a head m^3 which fits in and operates in a corresponding aperture e^5 in the vertical movable carriage e . The head m^3 is provided in the bottom thereof with a transverse recess m^4 , which is semi-circular in cross section, and in which is placed transverse bar m^5 of similar form in cross section, and the bottom of which is secured to a plate m^6 which is 65 held in place by a transverse lock plate m^7

secured to the carriage e by screws m^8 , all this construction being similar to that of the application hereinbefore referred to.

The rear end of the rock beam m^2 is provided with a head m^9 through which is passed a pin n on which is rotatably mounted a block bearing n^2 , and mounted on the crank of the crank shaft d is a split bearing n^3 , and two rods o are mounted in connection with the bearings n^2 and n^3 . The 70 rods o are threaded at their upper and lower ends and provided with nuts o^2 , and said rods are provided above the bearing n^3 with adjusting nuts o^3 above which are placed flanged collars o^4 , and the bearing n^2 is provided with downwardly directed hubs n^4 , and mounted on the rods o and resting on the collars o^4 are strong spiral springs o^5 , the tension of which may be adjusted by means of the nuts o^3 , and this construction 75 is also similar to that of the application hereinbefore referred to.

80 Mounted on the table b is a die bed b^4 which is movable forwardly and backwardly on said table and adjustable into different 85 positions, and said die bed is connected with said table by a tongue and groove construction, and is held in different positions of adjustment by set screws b^5 . The die bed b^4 is provided at one side thereof with a raised 90 bearing b^6 in which is mounted an adjustable screw bolt b^7 , and the opposite side of said die bed is provided with raised ears b^8 between which is pivoted a curved foot lever b^9 provided at its upper end with a weight 95 b^{10} , and passed through the lever below said weight is a set screw b^{11} , the inner end of which is adapted to bear on the side of the table b to limit the downward and inward movement of said lever.

100 Mounted on the die bed b^4 is a die support p having bottom flanges p^2 , and the die support p is secured to the die bed by means of angular-shaped clamps p^3 and screws or bolts p^4 . Mounted on the die support 105 p is a two-part die p^5 connected with the support by a tongue and groove construction, and the separate parts of the die are movable transversely of the support p and transversely of the machine, and one part 110 of said die is connected with the screw-bolt b^7 and the other part of said die is connected with the lever b^9 by link devices p^6 , this construction being also similar to that of the patent referred to, and the two-part die 115 forms as in said patent the workpiece holder.

120 The plunger f is connected with the head g^3 by a tongue and groove construction, comprising grooves formed in said head and corresponding tongues on the sides of the 125 plunger, as shown at f^2 , and plates f^3 secured to the head g^3 , and mounted in the top of the plunger f are guide pins f^4 having heads f^5 movable in the transverse space or chamber e^3 in the bottom of the plunger 130

carriage, and said pins pass downwardly through the top of the plunger *f* and are provided with transverse locking keys *f⁶*, and by means of this construction the 5 plunger *f* is connected with the plunger carriage and is movable transversely thereof, as will be readily understood.

I also provide a die block *f⁷* which is supported by the plunger *f*, said die block being 10 provided with a pin *f⁸* which passes upwardly through the bottom of the plunger *f* and is held therein by a key-pin or similar device *f⁹*. The die block *f⁷* must be rigidly held against rotation, and this may be done 15 by making the pin *f⁸* angular in form or in any other way.

The die block *f⁷* forms, in effect, a part of the plunger, and said die block is provided in the bottom thereof with spaced recesses *r*, 20 *r²* and *r³*.

At one side of the main frame is a supplemental frame plate *s* through which the main crank shaft *d* passes, and mounted on said main crank shaft is a gear *s²*, and an 25 arm *s³* is mounted on said shaft inwardly of the gear *s²*, and said arm passes forwardly and carries a gear *s⁴* and a pinion *s⁵* mounted on a stub shaft *s⁶* in the end of said arm, and the arm *s³* is provided with a downwardly 30 directed member *s⁷* having a curved slot *s⁸*, and the arm *s³* is rotatable on the shaft *d* and a bolt or screw *s⁹* is passed through the slot *s⁸* and into the frame plate *s*, and by means of this construction the arm *s³* may be vertically 35 adjusted.

I also employ a cam drum *t* mounted on a stub shaft *t²* secured in the side of the main frame, and said cam drum is provided with a gear *t³* which meshes with the pinion *s⁵*, and 40 said cam drum, in the construction shown, is what is called a built-up cam.

A rod *u* is passed through one side of the frame above the cam drum *t*, and said rod is provided at its inner end with a head *u²* 45 having a transverse slot *u³* through which is passed a pin *u⁴* which is secured to the inwardly directed portion of the part *g*, and the outer end of said rod is provided with an anti-friction roller *u⁵* 50 which operates in connection with a groove *t⁴* in the cam drum *t*, the form and arrangement of which is such as to operate the part *g* as hereinafter described.

One of the objects of this invention, as 55 hereinbefore set out, is to form a puppet valve or provide a puppet valve stem with a head, and the valve stem, in the construction and operation herein shown and described, constitutes the workpiece, and a rod *w* is shown supported or held by the two-part die *p⁵*, the construction of said die, or the 60 separate parts thereof, being the same as in the patent referred to, and in Fig. 6 I have shown or indicated the results produced by 65 the separate steps or operation of forming

the valve head on the rod or workpiece *w* which forms the stem *w²* of the complete valve.

The operation will be similar to that of the patent and application hereinbefore referred to, and will be readily understood by those familiar with the operation of this class of devices, the distinctive difference in this case being the means automatically operated by the plunger operating mechanism 75 for producing the result shown or indicated in Fig. 6.

The position of the parts shown in the drawing will be regarded as the normal position thereof, the two-part die *p⁵* being 80 shown supporting the rod or workpiece *w*. The arm *i²* is first grasped by a hand of the operator and the electrode carrier and plunger guide *g* is swung to the right so as to bring the electrode *i* in line with the rod or 85 workpiece *w*, in which operation the rod *u* moves outwardly, or to the left, and the anti-friction roller *u⁵* in the end thereof passes outwardly through a longitudinal groove *t⁵* which communicates with the 90 groove *t⁴* in the cam drum. The arm *i²* is then moved downwardly to bring the electrode *i* in contact with the rod or workpiece *w* and held in such position until said workpiece is heated to the desired temperature, 95 after which the electrode carrier and plunger guide is swung back into the position shown in Fig. 2 of the drawing, said last named movement of the part *g* being limited by the anti-friction roller *u⁵* striking the 100 part *t⁶* of the built-up cam on the cam drum *t*, as clearly indicated in Fig. 3 of the drawing.

The treadle *k⁵* is now depressed by a foot of the operator to operate the clutch mechanism to put the machine in operation, and by reason of the gear construction *s*, *s⁴*, *s⁵* and *t³*, one revolution of the crank shaft *d* will 105 depress the plunger carriage *e*, the plunger *f* and the die block *f⁷* and the rod or workpiece *w* will assume the form shown at *x* in Fig. 6. The treadle is held down or may be again operated to repeat the above operation and by reason of the built-up cam on the cam drum *t*, the electrode carrier and plunger guide *g* is automatically moved into 110 position by the rotation of said cam drum to bring the plunger *f* and the die block *f⁷* connected therewith in line to perform the second operation, the result of which is 115 shown at *x²* in Fig. 6.

The above operation is again repeated and the part *g* brought into line with the workpiece to perform the third operation producing the result shown at *x³* in Fig. 6. At 125 the end of this operation the cam drum will have made one complete revolution and will be back into the position shown in Fig. 2, as will also the electrode carrier and plunger guide *g* with the plunger *f* connected there- 130

with. The separate parts of the two-part die p^5 will then be operated by means of the foot lever b^9 to permit the detachment of the workpiece w and the insertion of another 5 workpiece therebetween.

In the operation of the apparatus it will be understood that the construction of the groove t^4 in the cam drum t is such that when the die block f^7 , or the recesses r, r^2 10 and r^3 therein are brought in line with the workpiece the same is locked or held against movement in such positions.

With the construction herein shown and described, it will be noted that it requires 15 three consecutive rotations of the crank shaft d to rotate the cam drum t one complete revolution, and the treadle and clutch operating mechanism of the apparatus which is the same as others of its class may 20 be controlled by holding the same out of operation for three complete revolutions of the crank shaft, or any means may be employed for rotating said shaft the desired 25 number of revolutions operated by one depression of the treadle as will be readily understood.

My invention is not limited to the exact timing of the cam drum, as herein shown and described, as in some cases the desired 30 result may be accomplished by a number of operations less or greater than three, in which event, the gearing which operates the cam drum will be correspondingly changed and the arm s^3 adjusted to suit the change in 35 the gears so as to rotate the cam drum the desired number of revolutions to one revolution of the crank shaft d , and the built-up cam on said cam drum would be changed to correspond with the change in the gears, 40 and the die block f^7 in this event would also be changed by increasing or decreasing the number of the recesses r, r^2, r^3 therein.

In other words, my invention is not limited to the number of consecutive operations 45 of the plunger to produce an article of manufacture, as herein shown and described, nor to the production of puppet valves, and changes in and modifications of the construction herein described may be made, 50 within the scope of the appended claims, without departing from the spirit of my invention or sacrificing its advantages.

It will be understood that the two-part workpiece holder p^5 constitutes the bottom 55 electrode, and this electrode together with the upper electrode i may be water-cooled as in other apparatus of this class, or as in the patent and application hereinbefore referred to, and in the accompanying drawing I have shown the usual copper conductors or leads y connected with the bottom electrode, and y^2 connected with the top electrode, and this construction and connection may be the same as in the patent and 60 application hereinbefore referred to, or as in

other apparatus of this class and, in practice, the conductors or leads y and y^2 are connected with a transformer in the usual manner, but which is not shown.

It will also be understood that the object 70 of the rods o and springs o^5 used in connecting the rear end of the rock beam m^2 with the shaft d is to give said rock beam a cushioned or relief action as in the application hereinbefore referred to, which will accommodate the crank shaft, rock beam and connected parts to changes in the strain thereon occasioned by changes in the character of the workpiece or pieces, or in the length, thickness or size thereof, and which will 75 80 prevent the breaking of, or injury to, said parts.

Having fully described my invention, what I claim as new and desire to secure by Letters Patent, is:—

1. An apparatus of the class described provided with a main shaft, a vertically movable plunger carriage in operative connection with the main shaft, a plunger suspended from said carriage and movable 90 transversely, thereof, a swinging plunger guide in connection with which said plunger operates, and means connected with said guide and the main shaft for moving said guide into different positions and for holding 95 the same in such positions.

2. An apparatus of the class described provided with a power shaft and a swinging electrode carrier and plunger guide, a cam drum geared in connection with the 100 power shaft, and an operating rod connected with said electrode carrier and plunger guide and in operative connection with said cam drum.

3. An apparatus of the class described 105 provided with a power shaft, a swinging electrode carrier and plunger guide, a gear mounted on the shaft, a movable arm mounted on said power shaft and carrying a gear which meshes with the gear on said 110 power shaft and a pinion, a suitably supported cam drum geared in connection with said pinion, and a rod connected with said swinging electrode carrier and plunger guide and in operative connection with said 115 drum.

4. An apparatus of the class described provided with a vertically adjustable table, a die bed adjustable on said table, a two-part die mounted on said die bed and 120 adapted to serve as a workpiece holder, means for adjusting the position of one part of said die, means for moving the other part of said die toward and from its mate, and a plunger die movable toward and from 125 the two-part die and parallel therewith.

5. An apparatus of the class described provided with an adjustable table, an adjustable die bed mounted on said table, a two-part die mounted on said die bed, 130

- means for adjusting one part of said die into different positions, means for moving the other part of said die toward and from its mate, said two-part die being adapted to 5 serve as a workpiece holder, a plunger die movable toward and from the two-part die, and an electrode mounted adjacent to the plunger die and movable toward and from the two-part die and adapted to operate in 10 connection with a workpiece supported by said two-part die.
6. An apparatus of the class described provided with an adjustable table, an adjustable die bed mounted on said table, a 15 two-part die mounted on said bed and one part of which is adjustable and the other movable toward and from the adjustable part, said two-part die being adapted to serve as a workpiece holder, a swinging 20 electrode carrier and plunger guide, a plunger movable through said guide and provided with a die having spaced forming elements, and an electrode supported by said guide and movable toward and from the 25 two-part die.
7. An apparatus of the class described provided with a two-part electrode adapted to serve as a workpiece holder, a swinging electrode carrier and plunger guide, a plunger 30 movable through said carrier toward and from the workpiece holder and provided with a die the face of which is provided with spaced forming elements, said plunger being movable toward and from the 35 workpiece holder and parallel therewith, an electrode movable through said guide toward and from the workpiece holder, and means for operating said plunger to produce by successive movement from a workpiece 40 mounted in said holder a complete article.
8. An apparatus of the class described provided with a swinging electrode carrier and plunger guide, a cam drum in operative connection with the main shaft of the apparatus, and an operating rod connected with 45 said guide and in operative connection with said drum.
9. An apparatus of the class described provided with a workpiece holder, a swinging 50 plunger die guide, a plunger die mounted in said guide and movable toward and from said work piece holder, said die having a plurality of spaced forming elements and means for bringing said elements successively in line with a workpiece supported 55 by said workpiece holder.
10. An apparatus of the class described provided with a workpiece holder, a transversely and vertically movable plunger die 60 mounted over said workpiece holder and provided in the bottom thereof with spaced recesses, means for heating a workpiece mounted in said holder by passing an electric current therethrough, means for moving 65 said plunger die to bring said recesses successively into line with said workpiece, and means for successively moving said die toward and from the workpiece in said holder to form the desired article.
11. An apparatus of the class described 70 provided with a workpiece holder, a plunger die movable toward and from said workpiece holder and parallel therewith and provided in its face with spaced recesses, means for heating a workpiece mounted in said holder by passing an electric current therethrough, means for moving said plunger die toward and from said workpiece holder, and means for moving said plunger die parallel 75 with said holder into different positions and for holding the same in such positions.
12. An apparatus of the class described 80 provided with a workpiece holder, means for heating a workpiece mounted in said holder by passing an electric current therethrough, a plunger die movable toward and from said workpiece holder and also movable parallel with said workpiece holder and adapted to be held in different positions in such parallel movement, and means for operating the plunger die when held in said different positions. 85
13. An apparatus of the class described 90 provided with a workpiece holder, a plunger die movable toward and from said workpiece holder and also movable parallel with said workpiece holder and adapted to be held in different positions in such parallel movement, means for operating the plunger die when held in said different positions, and an electrode movable toward and from said 95 holder and adapted to heat a workpiece supported therein. 100
14. An apparatus of the class described 105 provided with a workpiece holder, means for heating a workpiece mounted in said holder by passing an electric current therethrough, a plunger movable toward and from the workpiece holder and parallel therewith and provided with a die having 110 spaced forming elements, means connected with the power shaft of the apparatus for moving said plunger toward and from the workpiece holder, and means connected with said shaft for moving said plunger parallel 115 with the workpiece holder into different positions whereby successive movements of said plunger to bring said forming elements into operation with said workpiece will form therefrom a complete article. 120

In testimony that I claim the foregoing as my invention I have signed my name, in presence of the subscribing witnesses, this 20th day of October, 1916.

FRANK P. KOBERT.
